UNITED STATES PATENT OFFICE.

EDWIN H. BELL AND WILLIAM S. BOYCE, OF CHICAGO, ILLINOIS.

SHIM FOR TIE PLATES.

Application filed May 8, 1926. Serial No. 107,562.

This invention relates to devices used in railway tracks and more particularly to a relatively thin or shim-like device, to be inserted between a railway tie and a tie plate, and which for convenience we have herein described as a shim for tie plates.

Heretofore, due to climatic or other conditions rendering the rails uneven, it has been the practice on some railroads to move the spikes, raise the rails and the tie plates, and then shim and readjust the level of the track by inserting a thin wood shingle or a thin shim of wood on the tie and beneath the tie plate, and to then respike the rail and tie plate to the tie, the spike also passing through the shingle. When climatic conditions change, as for example, when the frost is out of the ground, these shingles are generally removed. The shingles are generally indented, mutilated and cut by the ribs and projections common to the under surfaces of tie plates, as the latter, under train loads, bear down upon the shingle. The life of the shingle therefore is, at best, only a matter of a few months.

The principal object of our invention is to construct a device of relatively thin wood, of fibre or of other suitable material, which shall have an initially formed, pressed or molded tie plate seat or surface corresponding with the contour, both transverse and longitudinal, of the bottom of the tie plate under which it is to be used, whether the tie plate has a configurated or a flat bottom surface. Another object is to produce a novel form of track device which may be used not only to shim up uneven rails already in track but which may be used when the track is initially laid. Another object is to produce a track device which may be held in position on the tie not only by the weight above it, but also by the rail spikes passing through spike holes cut through the shim; and finally to produce a track shim which is larger in surface area than the area of the tie plate with which it is to be used and which may be initially secured upon the tie by nails or screws, independently of the rail spikes passing through it.

These and other objects of our invention, and the advantages thereof, will more fully appear as we proceed with this specification; our invention consisting of a relatively thin, shim-like, track member having its upper surface initially conforming to the bottom

surface of the tie plate under which it is to be used and in the novel device and combinations of devices herein illustrated, described and more particularly pointed out in the claims appended hereto.

In the drawings:

Figure 1 shows in a perspective view, the end of a railway tie with a tie plate in position thereon, and our improved shim resting upon the tie and beneath the tie plate.

Figure 2 is a perspective view of our improved shim and a tie plate, off the tie, and in superposed relation but separated from each other.

Figure 3 is a perspective view of a modified form of shim.

Figure 4 is a vertical, longitudinal, sectional view of the modified form of shim shown in Figure 3 in operative position with respect to the tie and tie plate.

Figure 5 is a plan view of a modified form of our shim upon a tie, the outline of the tie plate being indicated in dotted lines.

Figure 6 is a bottom view of a modified form of tie plate with which our improved shim may be used.

Figure 7 is a transverse, vertical, sectional view of the plate shown, in the plane of the dotted line 7-7 of Figure 6, together with a transverse section of the form of shim to be used with said plate.

Figure 8 is a longitudinal, vertical, sectional view of a still further modified form of tie plate, with our modified form of shim shown in juxtaposition thereto.

Figures 9, 10, and 11 illustrate other modified forms of tie plate with which our improved shim may be associated.

Referring to Figures 1 and 2 of the drawing, A represents a tie of the usual construction, B a tie plate, and C our shim, as a whole. In this form it will be observed that the tie plate B is provided in its bottom surface, with a central, median, transverse groove or recess, the surface of which recess is indicated by the line 1; and also with end recesses 2, 2. Intermediate the end recesses and extending transversely of the plate, one on each side of the median recess 1, are downwardly projecting portions 3. The top of the tie plate B is provided with the usual rail bearing surface 4 and with a transverse, upwardly extending rail abutting shoulder or rib 5. Spike holes 6 are punched through the plate B.

Our shim C is provided with a flat bottom surface 7. Intermediate its ends and spaced apart by a recessed central portion 8 are two transversely extending grooves or recesses 9, 9. It will be seen by reference to Figure 2 that the top surfaces 10, 10, at each end of the shim, correspond with the recesses 2, 2, of the tie plate B, that the recesses 9, 9, of the shim correspond with the projecting surfaces 10, 3, 3, of the plate, and that the central or median projection 8 of the shim corresponds with the median recess 1 of the plate. The shim is also provided with spike holes 11, 11, arranged to register with the spike holes 6, 6, 15 of the plate.

It will be understood, as clearly illustrated by Figures 1 and 2, that the top surface of the shim C is shaped and configurated to correspond with the configuration of the bottom surface of the plate B and to form a firm seat for the plate B. It will be understood that the rails (not shown) of the track are placed upon the surface 4 of the plate B and are spiked down in the usual manner 20 by spikes (not shown), driven through the spike holes 6, 6, and 11, 11, firmly uniting the plate B and the shims C to the tie A.

Referring now to Figures 3 and 4, it will be understood that the shim D is of some 30 what larger surface area than the plate with which it is to be used,—that illustrated being a flat bottom plate. The shim D in this instance is provided with a recess in its top surface, of a length and width equal to the 35 length and width of the plate E so that said plate when seated will rest in the shim D as clearly shown in Figure 4. The shim D may be set directly on top of the tie in the same manner as the shim C (Figure 1), but this is 40 not imperative, as in some instances it may be desirable to slightly recess the tie A and to seat the shim D in said recess as shown in Figure 4, with the bottom surface 12 of the shim D below the top surface 13 of the tie.

45 In Figure 5 we have shown a shim F having a top surface configurated substantially the same as the shim C, but of a length greater than the length of the tie plate to be laid upon it. The dimension of the tie plate 50 is indicated by the dotted lines in Figure 5 and it will be observed that at either end of said plate the shim F has an extension 15 which constitutes means for fastening the shim to the tie A by screws 16 or nails 17 or 55 any other suitable means, said shim fastening means being independent of the spikes which will be driven through the spike holes 11, 11.

In Figure 6 is illustrated the well known 60 "compression" bottom form of tie plate G, which is provided, among other things, on its bottom surface, with a series of arcuate depressions 18. With such a tie plate we contemplate configurating our improved shim, shown in modified form at H in Figure 7,

with an undulating top surface 19 complementary to the grooves 18 of the tie plate.

In Figure 8 is shown a still further modified form I of our shim, having its top surface 20 configurated to correspond with and 70 form a seat for the under surface 21 of yet another type of tie plate, shown at J in Figure 8.

As before stated, Figures 9, 10 and 11 merely illustrate different configurations or 75 forms of bottom surfaces 22, 23, 24, of different types of tie plates with which our shims may be used,—it being understood that the seat for the tie plate will be formed in the top surface of the shim to correspond 80 with the particular form of bottom of tie plate with which it is to be used, whether the plate be that shown in these drawings or any other type of plate.

The method of shaping or configurating 85 the top surface of the shim to render it complementary to and a seat for the bottom of the particular type of tie plate with which the shim is to be used, is quite immaterial to our invention and may be varied as desired 90 by the manufacturer of the shim. In some cases, however, the wood may be steamed and its top surfaced by a suitable reciprocable die. In other cases the material may be pressed or molded by suitable means. 95

One of the advantages of our improved shim lies in the fact that when placed upon a tie in track and the tie plate is laid upon the shim, the plate is instantly seated and the rail, tie plate and shim may then be 100 spiked to the tie. The prompt initial seating of the tie plate in the configurated shim binds the two together in the sense that when movement of the rails in use in track tends to shift the plate, the tendency to shifting 105 movement is automatically imparted to the shim as well, so that relative movement between the tie plate and the tie is avoided, and relative frictional movement had only between the shim and the tie. And, as the 110 frictional engagement of the bottom of the shim with the top of the tie is greater than the normal frictional engagement of a metal tie plate with a wooden tie, the actual wearing of the tie due to frictional movement 115 upon it is substantially negative (the shim wearing out before the tie is injured). By inserting our new shim in track when the track is laid or new ties inserted, we greatly lengthen the normal life of the tie and lessen 120 the amount of readjustment of track which would otherwise result from changing climatic conditions. Moreover, the surface of the tie, not being mutilated or cut by direct contact with a metal tie plate, is not subject 125 to the usual decay due to moisture entering the tie as it is when mutilated.

We claim as our invention:

1. As a new article of manufacture, a 130 shim for tie plates, having its top surface

initially shaped complementary to the shape of the bottom of the tie plate with which it is to be used.

2. As a new article of manufacture, a shim made of relatively thin fibrous material, for use beneath a tie plate, the top surface of the shim being initially shaped complementary to the shape of the bottom of the tie plate with which it is to be used.

10 3. As a new article of manufacture, a shim for use in track between a tie plate and a tie, the shim being of soft texture relative to the tie plate and having a seat for the tie plate initially formed in its upper surface.

15 4. As a new article of manufacture, a shim for tie plates, having a tie plate seat molded or pressed initially in its top surface.

5. As a new article of manufacture, a shim of fibrous material for use between a tie and

a tie plate, having a greater surface area 20 than that of the tie plate with which it is to be used, the top surface of the shim having an initially formed seat for the tie plate, and means for fastening the shim to a tie.

6. As a new article of manufacture, a 25 shim for use between a tie and a tie plate, having a greater surface area than that of the tie plate with which it is to be used, the top surface of the shim having an initially formed seat for the tie plate, and means for 30 fastening the shim to the tie independently of tie plate fastening means.

In testimony, that we claim the foregoing as our invention we affix our signatures this 4th day of May, 1926.

EDWIN H. BELL.

WILLIAM S. BOYCE.
